UNITED STATES PATENT OFFICE

2,379,074

FORM-FOLDING MACHINE

Joseph Fossa, Lynn, Mass., assignor to United
Shoe Machinery Corporation, Flemington, N. J.,
a corporation of New Jersey

Application March 10, 1944, Serial No. 525,914

63 Claims. (Cl. 12—55.1)

This invention relates to machines for folding margins of work pieces and more particularly to a form-folding machine in which the folding is effected by a pair of cooperating dies which operate simultaneously along a substantial marginal portion of the work. The invention is illustrated herein as embodied in a machine for folding the marginal portions of quarters of shoe uppers although it should be understood that the invention is not limited to a machine for operating on work pieces of any particular shape.

One object of the present invention is to provide a form-folding machine in which the work is supported in fixed position on a stationary lower die and the folding is accomplished by a cooperating upper die which is so designed that the work is folded by the upper die moving in a single path normal to the work-supporting surface of the lower die. To this end and as a feature of the invention, the work piece is held on the lower die with its margin projecting beyond the edge of the die, the upper die having a portion which projects over the edge of the lower die and supports the projecting marginal portion of the work piece. Consequently, when the upper die is moved upwardly the margin of the work piece is turned upwardly at right angles to the body of the work and held there and upon subsequent downward movement of the upper die the upturned portion of the work piece is folded back upon the body thereof by the under surface of the projecting portion of the upper die.

The upper and lower dies of the machine illustrated herein are each formed in sections which are adjustable relatively to one another to accommodate work pieces of different sizes. In accordance with another object of the invention, provision is made for preserving the continuity of the edges of the dies as the sections thereof are separated to vary the effective size of the dies. To this end and in accordance with another feature of the invention, filler pieces are provided between each pair of die sections and are movable automatically from retracted or inoperative positions into positions between the die sections upon their separation. The filler pieces are urged by springs acting thereon into operative positions upon separation of the die sections. Latches cooperate with the filler pieces to hold them in their operative positions against retraction during operation of the machine and means are provided for releasing the latches and retracting the filler pieces when it is desired to move the die sections toward one another.

The illustrated machine is designed for fold-

ing the margins of shoe parts having both convexly curved and concavely curved marginal portions. In order that these portions may be readily folded and folded without the formation of pleats, provision is made for pinking the convexly curved portions and slitting the concavely curved portions of the work piece during the folding operation. To this end and as a further feature of the invention, the machine is provided with slitting and pinking knives which are normally held in elevated positions but are spring-urged downwardly to act on the curved marginal portions of the work piece supported on the upper die which thus acts as an anvil in cooperation with the knives. After the work piece is positioned and held on the work-support the knives are released for downward movement to act on the marginal portions of the work piece and are subsequently returned to their initial positions by upward movement of the upper die and are locked in their initial positions by latches provided for this purpose.

As another feature of the invention the knives are mounted for lateral adjustment simultaneously with the sections of the upper and lower dies so that when the dies are adjusted for work pieces of different sizes the slitting and pinking will take place along the proper marginal portions of the work.

Another feature of the invention relates to the provision of means in addition to presser feet by which the work is clamped on the work support for pressing the convexly curved marginal portions of the work and holding these portions in engagement with the adjacent surface of the upper die during the greater part of the folding operation so that these portions of the work will have the desired contours after they have been folded.

In accordance with a still further feature of the invention, the mechanism by which the upper die is moved through its cycle of operations includes means for maintaining the upper die in engagement with the work for a predetermined length of time at the completion of the folding operation to press the folded margin of the work piece. The upper die is moved by fluid-pressure-operated mechanism which includes an adjustable timing valve operative to cause the upper die to pause in its movements while in pressing engagement with the work for a length of time dependent upon the setting of the valve. At the end of this time the upper die moves upwardly to permit removal of the work from the machine and

then returns to its lowermost position in readiness for the next cycle of operation.

These and other features of the invention including various novel details of construction and combinations of parts will now be more particularly described by reference to the accompanying drawings and pointed out in the claims.

Fig. 52 is an angular view, partly in section, of a portion of the fluid-pressure mechanism;

Fig. 53 is a vertical section through the valve by which the length of time that the upper die remains in pressing engagement with the fold is regulated; and

Fig. 54 is a plan view, partly in section, of the fluid-pressure mechanism.

The machine is illustrated as being carried by a frame comprising legs 10 and 12 (Fig. 1) between the upper ends of which is secured a bed 14. The leg 10 may be attached directly to the floor and the leg 12 is carried by the bottom of a fluid reservoir 16 which is in turn supported on the floor. Secured to the upper surface of the bed 14 is a plate 18 carrying a lower die

20 which supports a work piece the margin of which is to be folded.

In the illustrated embodiment of the invention the lower die 20 is shaped to support the quarter of a shoe upper as shown in Fig. 3. This die is made of a plurality of sections which may be separated to the extent desired to accommodate quarters of different sizes. The die comprises a center section 22 which supports the heel end of the quarter, a pair of intermediate sections 24, and a pair of wing sections 26. As shown more clearly in Fig. 6 the center section 22 of the die includes a base plate 28 which is secured to the supporting plate 18, a block 30 fastened to the base plate 28 by screws 32 and a top plate 34 fastened to the upper surface of the block 30. The top plate 34 supports the work for the folding operation and is preferably formed of suitable yieldable material such as rubber to accommodate varying thicknesses of work. The intermediate sections 24 which are similar to each other and only one of which is illustrated in Fig. 6 each comprise a base plate 36, a block 38 and a top plate 40 of rubber or similar material. Similarly, the wing sections 26 each comprise a base plate 42, a block 44 and a top plate 45. The center section of the lower die is secured by the bottom plate 28 to the supporting plate 18 against movement in the machine. However, the intermediate sections 24 and the wing sections 26 are adjustable relatively to the center section 22 as shown more clearly in Figs. 4 and 5 so that the lower die may accommodate quarters of different lengths and widths.

For thus supporting the wing sections 26, the base plates 42 thereof are carried by arms 46 extending forwardly of the machine through slots cut in the under surfaces of the base plates 36 of the intermediate sections of the die and terminating forwardly thereof. Carried by the forward ends of the arms 46 are cam rolls 48 received by slots 50 formed in slides 52 supported in slideways in the supporting plate 18. The slots 50 in the slides 52 are so inclined that upon movement of the slides rearwardly of the machine from the position shown in Fig. 3 the arms 46 are moved in the direction of the arrows in Figs. 4 and 5, thus moving the wing sections 26 rearwardly away from the adjacent surfaces of the intermediate sections 24. This adjustment is made possible to accommodate quarters of different widths. For thus moving the slides 52 to adjust the die for different widths of quarters a slide 54 extending transversely of the slides 52 and supported thereon is provided. The slide 54 is formed with a pair of slots 56 which receive cam rolls 58 carried by the slides 52, the slots being so inclined that upon movement of the slide 54 to the right as viewed in Figs. 3 and 5 the slides 52 are moved rearwardly.

The slide 54 is guided for movement in slots formed in the under surfaces of racks 59 which are secured to slides 60 adjacent to the slides 52, the purpose of which slides will appear as the description proceeds. The right end of the slide 54 is formed with rack teeth 62 with which mesh the teeth of a gear segment 64 (Figs. 39 and 40) carried by a shaft 66 journaled in bearings 68 and 70 formed in upwardly extending arms of a bracket 72 secured to the supporting plate 18. The shaft 66 carries an arm 74 to the outer end of which is secured a handle 76 by which the arm 74 may be moved to rock the shaft 66 and move the slide 54 through the gear segment 64 and the

rack teeth 62. The arm 74 may be held in one of several different positions which correspond to different widths of shoes by a pin 78 slideable within the handle 76 and having a tapered end 5 portion engageable with one of a plurality of apertures 80 formed in a plate 82 secured to an extension 84 of the bracket 72. As shown in Fig. 41 the forward end of the pin 78 is formed with rack teeth 86 engageable with the teeth of a gear segment 88 journaled on a pin 90 in the outer end of the handle. The gear segment 88 is provided with other teeth 92 engageable with teeth 94 in the forward portion of a lever 96 pivoted at 98 in the inner end of the handle. A spring 100 acting 10 between the handle 76 and the lever 96 urges the forward end of the lever downwardly to move the pin 78 toward the plate 82 so that when the pin is registered with one of the apertures 80 it locks the arm 74 in the desired position and the wing sections of the die are locked against movement. It will be noted in Fig. 41 that the rearward end of the lever 96 has a portion engageable with the adjacent surface of the plate 82 so that when the forward end of the lever is raised against the force exerted by the spring 100, the handle 76 15 will be moved away from the plate 82 to assist in the withdrawal of the pin from the aperture in the plate. There is sufficient spring in the arm 74 by which the handle is carried to permit this movement of the handle. The lever 96 extends slightly below the handle 76 so that it may readily be grasped by the fingers of the operator when it is desired to effect a width adjustment of the lower die.

20 The intermediate sections 24 of the lower die are arranged for lateral movement relatively to the center section 22. They are each guided during this movement by a bar 102 (Figs. 3 and 6) carried at one end by the base plate 28 of the center section of the die and at their outer ends by the plate 18, there being a spacing washer 103 between the outer end of each arm and the plate corresponding in thickness to the thickness of the bottom plates 36 of the intermediate sections. 25 The blocks 38 of the intermediate sections are slotted to receive the bars 102 which thereby guide the intermediate sections in their movements. The base plates 36 of the intermediate sections carry rolls 104 which are received by slots 106 formed in the slides 60 carried by the plate 18 adjacent to the slides 52. The slots 106 are so inclined that upon movement of the slides 60 rearwardly of the machine, as indicated in Fig. 4, the intermediate sections are moved away from the center section 22 along the bars 102. As pointed out above, the arms 46 to which the wing sections are secured pass through slots formed in the under surface of the base plates 36 of the intermediate sections and, accordingly, these 30 arms will be moved with the intermediate sections so that the wing sections will be adjusted with the intermediate sections upon rearward movement of the slides 60. Inasmuch as the racks 59 through which the transverse slide 54 passes are secured to the slide 60 the slide 54 will also be moved rearwardly of the machine as indicated by the arrow in Fig. 4. This will cause the slides 52 to be moved rearwardly, thus effecting an additional movement of the wing sections so that they will be separated still further from the intermediate sections. Thus, upon adjustment of the lower die for quarters of different lengths by movement of the slides 60, both the wing sections and the intermediate sections of the die are moved relatively to the center section 35

and to each other, whereas only the wing sections are adjusted when the die is to be adjusted for quarters of different widths.

Movement of the slides 60 to adjust the die for different lengths of quarters is effected by the following mechanism. A shaft 110 (Figs. 3 and 39) is journaled in bearings 112 and 114 carried respectively by the bracket 72 and by a bracket 116 secured to the plate 18 at the opposite side of the machine. Secured to the shaft 110 are gear segments 118 and 120 which mesh with the teeth in the racks 59 secured to the slides 60 to impart motion to the slides as the shaft 110 is turned. The gear segment 120 is formed with a set of teeth 122 arranged at a 45° angle relatively to the shaft 110 which mesh with a similar set of teeth 124 of a gear segment 126 secured to a shaft 128 (Fig. 3) journaled in a bearing 130 of the bracket 116. An arm 132 secured to the shaft 128 is provided with a handle 134 (Fig. 39) similar to the handle 76 and including a pin receivable in one of a plurality of apertures 136 in a plate 138 secured to the bracket 116. Upon moving the arm 132 by the handle 134 the shaft 110 is rocked and acts through the gear segments and racks to move the slides 60 which adjust the intermediate sections and wing sections of the die as heretofore explained. It will thus be seen that by a simple manipulation of the handles 76 and 134 the die may be adjusted to accommodate quarters of different lengths or widths.

The line of fold of the work is determined by the rear edge of the die 20 which is the upper edge of the die as viewed in Fig. 3. In order to maintain the continuity of the edge when the sections of the die are separated to enlarge the die, provision is made for filling the spaces between the sections of the die. This is accomplished by the use of filler pieces 140 there being a set of these pieces between the center section of the die and each of the intermediate sections and between each of the intermediate sections and the wing sections.

To accommodate the filler pieces between the center section and the intermediate sections the blocks 38 of the latter sections are recessed as best shown in Figs. 6 and 34. The arrangement and mounting of the filler pieces between the center section and the intermediate section to the right of the center section will be described in detail and it should be understood that the other sets of filler pieces are similarly arranged. The filler pieces of each set are several in number and formed of thin plates pivotally mounted on a pin 142 (Fig. 34) extending from the block 38 into the recess. When the sections of the die are adjacent to each other the filler pieces are held in retracted positions by an extension 144 (Fig. 6) of the center block 38 but upon movement of the intermediate section away from the center section the filler pieces move about the pivot pin 142 into the space formed between the sections of the die, the number of filler pieces which are thus moved depending upon the extent of separation of the sections of the die. For thus moving the filler pieces a plurality of grasshopper springs 146 (Fig. 34) are provided. One end of each of these springs is anchored in a block 148 carried by a frame 150 secured in the recess in the block 38 and the other end of each of the springs bears against forwardly extending arms 152 of the filler pieces 140. The springs extend alternately in opposite directions from the supporting block 148 so that a sufficient number may be accommodated in the recess to correspond to

the number of the filler pieces. The filler pieces rest upon a rubber bearing block 154 and are provided with slots 156 through which the pivot pin 142 passes so that the filler pieces may be moved downwardly when pressure is applied to the work during the folding operation thus preserving the continuity of the yielding surface formed by the resilient top plates of the die sections.

In order to maintain the filler pieces in their operative positions when the die is expanded they are provided with forwardly extending arms 160 engageable with the rearward end of an arm 162 pivoted at 164 between spaced vertically extending arms 166 of the supporting frame 150. This arm is normally maintained in the position shown in Fig. 31 by its engagement with a lever 168 pivoted at 170 between the arms 166 of the supporting frame, this lever in turn being maintained in the position illustrated by a spring 172 (Figs. 31 and 32). When the die sections are separated and the filler pieces are moved from the positions shown in Fig. 31 to the positions shown in Fig. 32 by the springs 146, the arms 160 of the filler pieces cause the arm 162 to be moved upwardly until the arms 160 have cleared the end of the arm 162 whereupon the arm 162 drops into the position shown in Figs. 32 and 34 and the filler pieces are effectively locked thereby in their forward positions. The extent of movement of the filler pieces by the springs 146 is limited by engagement of the filler pieces with corresponding filler pieces of the upper die, to be described hereinafter.

In order to permit movement of the sections of the lower die toward each other to contract the die, the filler pieces must be withdrawn from their operative positions. For this purpose the rearward end of the lever 168 is engageable with the upper surfaces of the arms 152 of the filler pieces upon counterclockwise movement of the lever 40 thereby to move the filler pieces inwardly of the die against the forces exerted by the springs 146. Previous to engagement of the lever with the arms 152 of the filler pieces a cam surface 180 of the lever engages a depending portion 182 of the arm 162 to move this arm upwardly and unlock the filler pieces so that they may be moved rearwardly.

From the foregoing, it will now be seen that the filler pieces are moved one at a time by the springs 50 146 to fill the space between the center and intermediate sections of the die during separation of the sections and that the filler pieces are held against inward movement by the arm 162 to maintain the continuity of the edge of the die. Upon 55 movement of the lever 168 against the force of the spring 172 the arm 162 is moved out of locking engagement with the filler pieces and they are moved rearwardly by the inner portion of the lever into the position shown in Fig. 31 so that the sections of the die may be moved toward each other. The filler pieces between the intermediate sections and the wing sections are similarly mounted in recesses formed in the blocks 60 44 of the wing sections. The blocks 38 of the intermediate sections have extensions 184 (Fig. 6) against which the filler pieces rest when these sections of the die are close together.

The folding of the margin of the work piece is effected by an upper folding member or die which 70 is made of five sections corresponding to the five sections of the lower die. As illustrated in Fig. 9, the die consists of a center section 190, a pair of intermediate sections 192 and a pair of wing sections 194. As shown in Figs. 12 and 13, the die has a forwardly extending lip 198 which overlaps the

lower die slightly and has a slightly inclined top surface which supports the margin of the work to be folded. The work is so placed on the lower die that its marginal portion projects appreciably beyond the edge of the lower die onto the upper die. The folding of the work is effected by moving the upper die upwardly into the position shown in Fig. 21 which causes the outwardly projecting marginal portion of the work to be turned upwardly after which the upper die moves downwardly as shown in Figs. 22 and 23 to turn the margin of the work back upon the body portion. In order thus to turn the marginal portion back as shown in these views, the under surface of the lip 198 of the upper die is slightly inclined and is connected to the adjacent vertical face of the die by a curved portion. The fold is pressed by the upper die when moved into the position shown in Fig. 24 after which the die is again moved upwardly to permit withdrawal of the work as shown in Fig. 25 and then returned to its lower position as shown in Fig. 26 preparatory to the next folding operation. It will be understood that the width of the fold will depend upon the amount of overlap of the work beyond the edge of the lower die. The vertical portion of the upper die depending below the lip 198 holds the upturned margin of the work upright and limits the outward squeeze of the work as it is folded by the downward movement of the upper die as shown in Figs. 22 and 23.

The upper die sections are secured by screws 200 (Fig. 16) to the under surfaces of vertically extending blocks these being five in number corresponding to the number of sections of the die. The center die section 190 is secured to a block 204 (Figs. 7 and 28) which is in turn secured by screws 206 to a plate 208 (Figs. 1 and 10) which is carried by the under side of a vertically movable crosshead 210. The under surface of the crosshead, as shown in Fig. 10, is flanged to provide spaces between the crosshead and the plate 208 for a purpose which will appear as the description proceeds. The crosshead 210 is secured to the upper ends of rods 212 the lower ends of which are connected to eccentric straps 214 driven by eccentrics 216 (Fig. 44) mounted on a rock shaft 218 journaled in bearings 219 (Figs. 1 and 44) carried by the legs 10 and 12 of the machine frame. Upon oscillation of the rock shaft the crosshead is reciprocated vertically to carry the die section 190 up and down relatively to the lower die.

The intermediate sections 192 of the upper die are carried by vertically extending blocks 220 (Figs. 7 and 28) to the upper ends of which are secured pins 230 which pass through slots 232 (Figs. 7, 8 and 10) in the plate 208. These pins are provided with heads 234 which rest on the upper surface of the plate 208 to support the blocks therefrom but permit the blocks to be adjusted thereby to permit adjustment of the intermediate sections of the upper die corresponding to the adjustment of the intermediate sections of the lower die. The wing sections 194 of the upper die are carried by blocks 238 (Figs. 7 and 28) which are similarly supported by pins 240 from the plate 208 which is provided with slots 242 so that the wing sections of the upper die may be adjusted in the same manner as the wing sections of the lower die.

In order to guide the sections of the upper die in their vertical movements and to permit their adjustment conjointly with the adjustments of the lower die sections, vertical guide bars 244 (Fig. 28) are secured by screws 246 to the upper die sec-

tions and depend therefrom. These guide bars are confined between pairs of vertical flanges 248 extending rearwardly from the blocks of the lower die, as best shown in Figs. 3 and 28, and plates 250 secured to the flanges. It will thus be seen that as the sections of the lower die are adjusted to accommodate quarters of different sizes, the upper die sections will be moved with them, the connections between the blocks carrying the upper die sections and the supporting plate 210 permitting the upper die sections to be adjusted in the same directions as the lower die sections.

The blocks 220 of the intermediate sections of the upper die are provided with lateral extensions 254 (Fig. 28) which overlap the rearward surfaces of the blocks 204 and 238 of the center and wing sections of the upper die. The extensions 254 are formed with spaced depending ears 256 carrying pins 260 from which are suspended filler pieces 262. The lower end of these filler pieces, as shown in Figs. 31 to 33, are similar in shape to that of the upper die members. When the upper die sections are close together, the filler pieces are held in retracted positions behind the blocks of the center and wing sections of the upper die, as shown in Figs. 28 and 31, but are movable into positions between the dies when they are moved apart, as shown in Fig. 32.

For thus moving the filler pieces a plurality of grasshopper springs 264 act upon the rearward surfaces of the filler pieces. One end of each of these springs is carried by a block 266 in an angular plate 268 secured at its upper end by screws 270 to the upper rearward portion of the block 220. This plate has a downward extension 271 secured by a screw 273 to the adjacent guide bar 244 (Fig. 27). The screw passes through a slot 275 in the plate 250 which permits vertical movement of the plate 268 with the guide bar 244. The screw carries a roll 277 engageable with the sides of the slot 275. The springs 264 extend alternately in opposite directions in the same manner as the springs 146 (Fig. 34) so that space will be available to provide one spring for each filler piece. The other ends of the springs are secured at 272 to the rearward surfaces of the filler pieces. For locking the filler pieces in their operative positions as shown in Fig. 32, a latch 274 associated with each set thereof is provided. These latches are pivoted on pins 276 between spaced forwardly extending ears 278 at the lower ends of the angular plates 268. Springs 280 carried by the plates 268 act upon upwardly extending portions 282 of the latches to urge the forward portions upwardly. When the filler pieces are moved into the positions shown in Fig. 32 the latches are received within recesses 284 in the lower rearward surfaces of the filler pieces to hold them in operative positions. In order to reset the filler pieces or move them into their inoperative positions when it is desired to move the sections of the die together, the latches 274 are retracted. For this purpose, vertically extending rods 286 are mounted for sliding movement in grooves formed in the rearward surfaces of the angular plates 268 and are confined therein by plates 288 secured to the rearward surfaces of the plates. Near their lower ends these rods are formed with recesses 290 in which the extensions 282 of the latches normally seat. However, upon upward movement of the rods 286, as shown in Fig. 33, the portions 282 of the latches are moved out of the recesses causing the forward ends of the latches to be moved downwardly. A slight further upward movement of the rods 286, after

the latches have been released, is effective to move the filler pieces back into their retracted positions. The filler pieces are provided with projections 292 extending rearwardly from the pins 260 on which they are pivoted and these projections are arranged to be engaged by forwardly projecting arms 294 formed at the upper ends of the rods 286. These arms 294 are movable in slots 296 formed near the upper end of the angular plates 268 and downward movement of these rods is limited by engagement of lugs 298 with the bottoms of the slots. After the rods 286 have released latches 274, the arms 294 engage the projections 292 of the filler pieces and swing the filler pieces to retract the lower portions, as shown in Fig. 33.

The retraction of the lower and upper filler pieces by the mechanisms heretofore described is effected simultaneously so as not to interfere with the adjustment of the upper and lower sections of the die which, as has been described, is effected simultaneously. The mechanism for retracting the filler pieces will now be described. Below the forward ends of each of the levers 168 associated with the lower die for resetting the filler pieces 140 are headed pins 300 (Figs. 3 and 36), these being four in number corresponding with the number of sets of filler pieces associated with the lower die. These pins are vertically slidable in sleeves 302 which have reduced lower portions received by holes in the lower die-supporting plate 18. These pins are arranged to be moved upwardly in unison when it is desired to retract the filler pieces, the pins acting on the levers 168 (Fig. 33) to move them in a counterclockwise direction, as viewed in that figure. Similar pins 304 are located below the lower ends of the rods 286, these pins being similarly slidable in sleeves 306 supported from the plate 18 so that upon upward movement of these pins the rods 286 are moved upwardly to reset the filler pieces 262 as heretofore described.

For thus moving the pins 300 and 304, the following mechanism is provided. Secured to the under side of the bed 14 of the machine frame is a plate 310 (Figs. 37 and 38) provided with depending bearings 312 (Fig. 36) in which are journaled rock shafts 314. Upon the outer ends of these rock shafts are secured arms 316 the forward ends of which underlie the lower end of the pins 300 which pass downwardly through the bed 14 and the plate 310. Secured to the under surface of the plate 310 are fixed shafts 318 on which are journaled levers 320 each of which has a pair of rearwardly extending arms 322 which underlie the lower ends of the pins 304. The forward ends of the levers 320 are connected by links 324 (Fig. 37) to forwardly extending arms 326 secured to rock shafts 328 journaled in bearings 329 depending from the under side of the plate 310. The arms 316 associated with the outer of the pins 300 are extended rearwardly of the rock shafts 314 and are connected by links 330 to the forward ends of levers 332 pinned to the rock shafts 328. Upon upward movement of the rearward ends of the levers 332 the forward ends of the arms 316 move upwardly to move the pins 300 upwardly and through the mechanism heretofore described to reset the filler pieces associated with the lower die. At the same time the rock shafts 328 are turned in such directions that the arms 322 of the levers 320 move upwardly to move the pins 304 and reset the filler pieces associated with the upper die.

The rearward ends of the levers 332 rest upon

a cross bar 336 formed at the lower end of a rod 338 slidable vertically through a bracket 340 extending rearwardly from the bed 14. The upper end of the rod 338 (Fig. 38) is connected to the 5 armature of a solenoid 342 secured by a bracket 344 to a vertical housing 346 which is secured by screws 348 to the bed 14. When the solenoid 342 is energized, the rod 338 is pulled upwardly to move the levers 332 in a counterclockwise direction as viewed in Fig. 38 which, through the mechanism which has been described, moves the pins 300 and 304 upwardly to reset the latches. For energizing the solenoid 342 a treadle 350 is provided, journaled on a shaft 352 supported by 10 the leg 10 (Fig. 1) of the machine frame and by the adjacent wall of the reservoir 16. This treadle has an upwardly extending arm 354 connected by a link 356 to an arm 358 of a switch 360 secured to a crossarm 362 which is carried 15 by the legs 10 and 12. Upon depression of the treadle 350 the switch 360 is operated to close a circuit to the solenoid 342 which is thus energized and all the filler pieces are reset. The operator maintains his foot on the treadle 350 20 until the dies are adjusted properly for size, after which the treadle is released thus permitting any existing spaces between the die sections to be occupied by the appropriate number of filler pieces.

For holding the work on the lower die in its proper position during the folding operation, a plurality of presser feet are employed for engagement with the work near the edge to be folded. As shown herein these presser feet are 25 seven in number and include a presser foot 370 (Fig. 9) associated with the central die section, a pair of presser feet 372 associated with the intermediate die sections, a pair of presser feet 374 engageable with the work at the convexly 30 curved portions at the inner ends of the wing sections and presser feet 376 associated with the remaining portions of the wing sections. When the machine is at rest these presser feet occupy 35 raised positions in which they are located a substantial distance above the work support so as not to hinder the proper placing of the work thereon. In placing the machine in operation these presser feet are moved downwardly to 40 clamp the work against the top surface of the lower die and engage the work along a substantially continuous line from one end of the die to the other, as shown in Figs. 9 and 11.

The mounting and operation of the presser feet 376 associated with the wing sections of 45 the die will now be described. Inasmuch as the mounting of the presser feet at each end of the machine is substantially identical, only that one shown at the right end of the machine in Fig. 11 is described in detail. This description also applies generally to the mounting and operation 50 of the presser foot 370. The presser foot 376 (Figs. 12, 13 and 14) is secured to the lower end of a slide 380 which is movable vertically in a slideway 382 (Figs. 7 and 28) formed in the front 55 face of the die block 238. The slide is maintained in the slideway by a plate 384 secured to the block. The slide is maintained in an elevated position when the machine is at rest by a tension spring 386 (Fig. 12) the lower end of 60 which is secured to a pin 388 in the lower end of the slide 380 and the upper end of which is secured to a pin 390 extending forwardly from the block 238. The forward portion of the slide 380 is slotted at 392 to receive the lower rectangular portion 394 of a plunger having a reduced 65 70 75

noid 788, thereby operating the lever 760 to return the valve member 732 to the position shown in Fig. 44, whereby the pressure fluid is admitted to the cylinder 726 and the parts are returned to their original positions. During this time the cam 810 (Fig. 52) has operated the lever 816 to return the valve member 820 into the position shown and the machine comes to rest.

The operation of the machine will now be summarized. The upper and lower dies are first properly adjusted as to the length and width of the quarter, the margin of which is to be folded, by manipulation of the arms 132 and 14 (Figs. 1 and 39). If the quarter is smaller than that for which the dies have previously been set, it will be necessary to retract the filler pieces which have occupied the spaces between the portions of the dies and this is accomplished by depression of the treadle 350 which operates through the solenoid 342 (Fig. 38) to lift the pins 300 and 304 which thereby move the filler pieces inwardly of the operating edges of the dies, as shown in Figs. 31 and 33. After the dies have been properly adjusted as to size, the treadle 350 is released and if any spaces exist between the sections of the dies they will be occupied by the appropriate number of filler pieces which are moved into operative positions under spring pressure and held by their latches against retraction.

With the dies now adjusted as to size, a quarter Q is placed on the supporting surface of the lower die with its upper edge in engagement with the vertical ribs 460 of the upper die blocks, as shown in Fig. 11. The heel end of the treadle 640 is now depressed, thereby closing the switch 662 (Figs. 46 and 48) which energizes the solenoid 630 and moves the valve member 590 to the right, thereby admitting fluid under pressure into the cylinder 576. The piston 574 now rises until the rod 572 engages the stop 666. This movement of the piston causes the plate 406 to move down, depressing the sleeves which extend upwardly through the crosshead 210, thereby moving the presser feet into engagement with the work. The work is now clamped along its marginal portion by various presser feet, as shown in Fig. 11, and the machine now comes to rest. At this stage, if the work has not been properly positioned in the machine the presser feet may be lifted to free the work by operation of the switch 696 which energizes the solenoid 636 (Fig. 46) to return the valve member 590 to the position shown, whereupon the plate 406 is raised by pressure of the spring 538 and the presser feet are moved by spring pressure upwardly out of engagement with the work.

Assuming that the work has been properly positioned in the machine, the valve member 590 begins as the die reaches its uppermost position the engagement with the work, the toe end of the treadle 640 is depressed, as shown in Fig. 49. This causes closure of the switch 778 and energization of the solenoid 768 (Fig. 44), thereby moving the valve member 738 to the left and admitting fluid under pressure into the cylinder 724. The rock shaft 218 is now moved in a clockwise direction to move the upper die upwardly to turn the margin of the work at right angles to the body portion as shown in Fig. 21. This movement of the rock shaft also turns the cam shaft 528 in the direction of the arrow. At the beginning of this upward movement of the upper die, the cam 526 (Fig. 43) permits downward movement of the latch-releasing plate 454, whereupon the latches 446 and 494 release the pinking and slitting knives which are forced downwardly un-

- der spring pressure, as shown in Fig. 20, thereby conditioning the curved portions of the work for the folding operation. As the upper die continues its upper movement the knives move with it and the cam 526 resets the latch-releasing plate 454. As the die reaches its uppermost position the latches are moved into their operative positions in which they hold the knives in elevated positions. Prior to the completion of the upward movement of the upper die, the cam 680 (Figs. 46 and 47) permits raising of the stop 666 so that the piston 574 may move upwardly still further, thereby depressing the plate 406 sufficiently to move the corner tools 462 into operative positions, as shown in Fig. 21, in which the convexly curved marginal portions of the work are held in engagement with the adjacent vertical surfaces of the upper die 194. As the upper die reaches its uppermost position, the switch-actuating arm 780 (Fig. 45) closes the switch 786 to energize the solenoid 788 which causes movement of the valve member 738 back into its initial position. Meanwhile, the cam 794 (Figs. 48 and 50) opens the switch 778 in the event that the operator has neglected to remove his foot from the toe end of the treadle so that the solenoid 768, acting on the valve member 738 is deenergized. The crosshead and upper die are now moved downwardly, during which the cam shaft 528 is given another quarter turn and the cam roll 566 (Fig. 46) moves into the depression 684 of the cam 568. This permits the fulcrum 542 of the lever 536 to be elevated slightly so that the plate 406 is moved upwardly by pressure of the spring 538 sufficiently far to permit retraction of the corner tools, as shown in Fig. 22. This takes place just previous to the beginning of the folding of the upturned margin of the work by the lip 198 of the upper disc. During the final downward movement of the upper die the cam roll 566 (Fig. 46) moves into the depression 686 of the cam 568, permitting still further upward movement of the fulcrum 542 of the lever 536, whereupon the plate 406 moves upwardly to release the presser feet as the folding operation is completed (Fig. 24). During the last part of this downward movement of the upper die the cam 810 (Figs. 44 and 52) operates the lever 816 to move the valve member 820 to the right, admitting fluid into the cylinder 832 below the piston 834. Pressure fluid now flows into the cylinder at a rate dependent upon the setting of the needle valve 826 so that after a predetermined length of time the lever 760 is operated to move the valve member 738 to the left. The length of time required to cause this operation is readily adjusted by the needle valve so that the upper die will remain in pressing engagement with the folded margin of the work the proper length of time.
- The upper die is now moved upwardly again by operation of the shaft 218 until it reaches the position shown in Fig. 25, during which the now completely folded work is removed by the operator from the machine. During this time the cam 810 (Fig. 52) returns the valve member 820 to the position shown and the cam 682 (Figs. 46 and 47) moves the stop 666 back toward its initial position. The valve member 590 is also moved back to its initial position by the cam 692 on the cam shaft 528 acting on the roll 690 and the fulcrum of the lever 536 is returned to its initial position. As soon as the upper die reaches its uppermost position, the switch 786 is again closed by the arm 780 to energize the solenoid 788, thereby returning the valve member 738 to the position

shown in Fig. 44 which moves the drive shaft 218 back to its initial position and causes the die to move downwardly into the position shown in Fig. 26. During this movement the cam shaft 528 is moved through its last quarter turn into its initial position and the machine comes to rest with the parts all in their initial positions.

Having thus described the invention, what I claim as new and desire to secure by Letters Patent of the United States is:

1. In a form-folding machine, a fixed lower die arranged to support a work piece the margin of which is to be folded, means for holding a work piece in fixed position on the lower die, an upper die constructed and arranged to fold the margin of the work piece while it is held on the lower die in response to movements of the upper die in a fixed path substantially normal to the work-supporting surface of the lower die, means constraining the upper die for movements in said fixed path, and means for thus moving the upper die.

2. In a form-folding machine, a lower die arranged to support a work piece with the margin to be folded extending outwardly beyond an edge thereof, an upper die at said edge of the lower die and arranged to support said margin of the work piece, said upper die having a portion projecting laterally over the edge of the lower die, and means for reciprocating said upper die in a path normal to the work-supporting surface of the lower die.

3. In a form-folding machine, a lower die arranged to support a work piece with the margin to be folded extending outwardly beyond an edge thereof, an upper die at said edge of the lower die and arranged to support said margin of the work piece, said upper die having a portion projecting laterally over the edge of the lower die and arranged upon upward movement of the upper die to turn the marginal portion upwardly and to fold the upturned marginal portion upon downward movement of the upper die, said upper die also having a vertical portion depending from the laterally projecting portion to hold the upturned margin of the work upright and to limit the outward squeeze of the work during folding of the margin, and means for reciprocating the upper die in a path normal to the work-supporting surface of the lower die.

4. In a form-folding machine, a lower die arranged to support a work piece with the margin to be folded extending outwardly beyond an edge thereof, an upper die at said edge of the lower die and arranged to support said margin of the work piece, said upper die having a portion projecting laterally over the edge of the lower die and arranged upon upward movement of the upper die to turn the marginal portion upwardly and to fold the upturned marginal portion upon downward movement of the upper die, said upper die also having a vertical portion depending from the laterally projecting portion to hold the upturned margin of the work upright and to limit the outward squeeze of the work during folding of the margin, means for maintaining said vertical depending portion close to the edge of the lower die, and means for reciprocating the upper die in a path normal to the work-supporting surface of the lower die.

5. In a form-folding machine, a lower die arranged to support a work piece with the margin to be folded extending outwardly beyond an edge thereof, an upper die at said edge of the lower die and having a surface arranged to support said margin of the work piece, gage means associated

with the upper die to determine the amount of overlap of the work piece beyond the lower die, fold-pressing means carried by the upper die extending between the work piece and the lower die when the machine is at rest, and means for reciprocating the upper die in a path normal to the work-supporting surface of the lower die.

6. In a form-folding machine, a fixed lower die arranged to support a work piece with the margin to be folded projecting outwardly beyond an edge thereof, an upper die, means constraining said upper die for movement in a path normal to the work-supporting surface of the lower die, said upper die including means for turning up the margin of the work upon movement of the die in one direction and for folding the turned-up portion of the work upon movement of the die in the opposite direction, and means for thus moving the upper die.

7. In a form-folding machine, a fixed lower die arranged to support a work piece with the margin to be folded projecting outwardly beyond an edge thereof, an upper die, means constraining said upper die for movement in a path normal to the work-supporting surface of the lower die, said upper die including means for turning up the margin of the work upon movement of the die in one direction and for folding the turned-up portion of the work upon movement of the die in the opposite direction, means for thus moving the upper die, and means for holding the work piece on the lower die during the folding operation.

8. In a form-folding machine, a fixed lower die arranged to support a work piece with the margin to be folded projecting outwardly beyond an edge thereof, an upper die, means constraining said upper die for movement in a path normal to the work-supporting surface of the lower die, said upper die including means for turning up the margin of the work upon movement of the die in one direction and for folding the turned-up portion of the work upon movement of the die in the opposite direction, means for thus moving the upper die, and means for holding the upturned convexly curved marginal portions of the work against the adjacent surface of the upper die during its downward movement.

9. In a form-folding machine, a folding member comprising a block having a projecting lip extending laterally from the upper portion of the block, the under surface of said lip being inclined downwardly toward the body portion of the block and being curved at its inner portion where it merges with the block.

10. In a form-folding machine, a lower die arranged to support a work piece with the margin to be folded projecting outwardly beyond an edge thereof, an upper die at said edge of the lower die, the top of the upper die projecting over said edge of the lower die and forming a support for the projecting margin of the work piece, the under surface of the projecting portion of the upper die being connected by a concavely curved portion with the adjacent vertical portion of the upper die to assist in folding the material upon downward movement of the upper die after the margin of the material has been turned upwardly by an upward movement of the upper die.

11. In a form-folding machine, a lower die for supporting a work piece the margin of which is to be folded, said die including a resilient work-supporting surface, and means for folding the margin of the work piece and pressing the folded margin against the resilient work-supporting surface of the lower die.

12. In a form-folding machine, a lower die ar-

576 thereby moving the plate 406 downwardly and forcing the presser feet into engagement with the work. The solenoid 630 is energized by depressing the heel end of a treadle 640 pivoted at 642 in a bracket 644 which may be attached to the floor. The treadle 640 is connected by a vertically extending link 646 to the forwardly extending arm 648 of a bell-crank lever 650 carried by a shaft 652. The bell-crank lever 650 includes a vertically extending arm 654 which is connected by a link 656 through a pin-and-slot connection 658 to the arm 660 of a switch 662. The switch arm 660 is normally held by a spring (not shown) in a forward position in which the switch is open. Upon depressing the heel end of the treadle 640 the switch arm 660 is moved in a clockwise direction into the position shown in Fig. 48 in which a circuit is completed to the solenoid 630, whereupon the valve member 590 is moved to the right to admit fluid pressure to the cylinder 576.

The upward movement of the piston 574 at this time is limited to permit the downward movement of the plate 406 only sufficiently to move the presser feet into engagement with the work without moving the corner tools into operative positions. For thus limiting this upward movement of the piston 574 an adjustable stop 666 is carried by the forward end of an arm 668 pivoted at 670 (Fig. 47) between spaced ears of a bracket 672 carried by the cross arm 362 (Fig. 2). The arm 668 is prevented from dropping below the position illustrated in Fig. 47 by a projection 674 extending rearwardly from the pivot 670 and engaging the under surface of the bracket 672. A cam roll 676 carried by spaced upwardly projecting ears 678 of the arm 668 is arranged to engage the periphery of a cam 680 carried by the cam shaft 528 for adjustably limiting the upward movement of the arm 668, thereby variably to limit the upward movement of the piston 574 to obtain a predetermined cycle of operations. When the machine is at rest the cam occupies the position shown in Figs. 46 and 47 in which the arm 668 is held against any upward movement. Accordingly, engagement of the upper end of the piston rod 572 with the stop 666 to stop downward movement of the plate 406 will take place before the corner tools have moved into engagement with the work. After the cam shaft 528 has rotated a slight amount in the direction of the arrow the cam roll 676 rides into a depression 682 in the periphery of the cam 680, thus permitting upward movement of the arm 668 and further upward movement of the piston 574 during which the corner tools are moved into engagement with the work.

At a predetermined time in the operation of the machine the cam 568 is rotated to a position in which the cam roll 566 rides into a depression 684 in the periphery of the cam. This permits the lever 548 to be moved slightly in a clockwise direction, whereupon the spring 538 acting on the rod 534 moves this rod upwardly to a position determined by the engagement of the cam roll 566 with the cam 568. During this time the lever 536 pivots about its connection to the piston rod 572. This slight upward movement of the rod 534 is sufficient to move the corner tools out of engagement with the work and into their retracted positions. As the cam shaft 528 continues rotating, the cam roll 566 rides into another depression 686 of the cam which permits still further upward movement of the plate 406 by the spring 538 to move the presser feet out of engagement with the work. Finally the valve mem-

ber 590 is moved back into the position shown in Fig. 46 by a cam 688 carried by the cam shaft 528 acting on a roll 690 journaled at the upper end of the arm 624 of the lever 618. After this cam has been rotated somewhat over a half revolution from the position shown, a high portion 692 thereof acts on the roll 690 to turn the lever 618 in a clockwise direction, thereby returning the valve member 590 to closed position and permitting the pressure fluid to exhaust through the opening 594 to the fluid reservoir.

The solenoid 636 connected to the lever 618 is provided merely for returning the valve member to closed position at the beginning of the machine operation to lift the presser feet if the work has been incorrectly positioned on the lower die. The return of the valve to this position will lift the plate 406 so that the presser feet are returned to their elevated positions, thereby permitting shifting of the work if necessary. For thus energizing the solenoid 636 a manually-operated switch 696 at the front of the machine (Figs. 1 and 2) is provided.

The cam shaft 528 is moved 90° during each movement of the crosshead 210 by the rock shaft 218 which is arranged for oscillatory movement. The crosshead partakes of two upward movements and two downward movements during the operation of the machine to carry the upper die through its entire cycle. For thus moving the cam shaft 528, a ratchet 700 is keyed thereto (Fig. 44) on opposite sides of which are journaled arms 702 and 704. These arms carry pawls 706 and 708 for engagement with teeth 710 of the ratchet 700. The outer ends of the arms are connected by links 712 and 714 respectively and by a pin 716 to an arm 718 secured to the eccentric 216 (Fig. 45). Upon movement of the rock shaft 218 in a clockwise direction, as viewed in Fig. 44 to move the upper die upwardly, motion is transmitted by the pawl 708 to the ratchet 700 to move the cam shaft 528 in the direction of the arrow through 90° of rotation. Upon reverse rotation of the rock shaft 218 to return the upper die to its lower position the pawl 706 acts on the ratchet 700 to turn the cam shaft 528 another 90° in the direction of the arrow. Thus, for two turning movements of the rock shaft 218 in each direction the cam shaft 528 is turned through one complete revolution.

The rock shaft 218 is operated by a pair of pistons 720 and 722 movable in cylinders 724 and 726 into which pressure fluid flows selectively from a valve chamber 728 in the valve housing 582. The valve chamber 728 is provided with an inlet port 730 which communicates by a passageway 732 (Fig. 54), a valve chamber 734 and a passageway 736 with the valve chamber 584. Slidable within the valve chamber 728 is a valve member 738 carrying a pair of valve elements 740 and 742. With the valve member in the position shown in Fig. 44, the valve element 740 cuts off the flow of fluid pressure to the cylinder 724, which cylinder is connected by an exhaust port 746 with the fluid reservoir. At this time fluid under pressure flows through a passageway 748 into the cylinder 726 thereby holding the piston 722 in the position shown, the element 742 closing off an exhaust port 749 for the fluid in the cylinder 726.

The pistons 720 and 722 include rods 750 and 752 which are connected to the opposite ends of a crank arm 754 keyed to the outer end of the rock shaft 218. Upon movement of the valve member 738 to the left, fluid under pressure

enters the cylinder 724 and the fluid in the cylinder 726 exhausts through the port 749. Accordingly the piston 720 is moved upwardly to turn the rock shaft 218 in a clockwise direction, sufficiently to move the crosshead 210 to its uppermost position and carry the upper die into the position shown in Fig. 21. When the valve member returns to the position shown, the pistons are moved in the opposite directions thereby returning the crosshead 210 to its lowermost position and during each of these movements of the shaft 218 the cam shaft 528 is turned 90° in the direction of the arrow.

The valve member 738 includes a stem 750 which projects rearwardly of the valve chamber and is pivoted to the lower end of a lever 760 pivoted on a shaft 762 mounted in the arm 12 of the machine frame. The lever 760 is connected at its upper end by a link 764 to the armature 766 of a solenoid 768. Upon energizing the solenoid the armature is drawn inwardly, thereby turning the lever 760 in a clockwise direction and moving the valve member 738 to admit fluid pressure to the cylinder 724. The energization of the solenoid is effected by depression of the toe end of the treadle 640 as follows. The arm 654 of the bell-crank lever 650 is connected to an arm 770 extending rearwardly of the machine and provided with a recess 772 (Fig. 48) within which is positioned a laterally extending pin 774 carried by an arm 776 of a switch 778. Upon movement of the treadle 640 from the position shown in Fig. 48 to the position shown in Fig. 49 by depression of its toe end, the bell-crank lever is moved in a counterclockwise direction to move the switch arm 776 of the switch 778 to close a circuit through the switch. At this time the arm 660 of the switch 662 is returned to open position. The closure of the circuit through the switch 778 energizes the solenoid 768 to operate the valve member 738 (Fig. 44), thereby admitting pressure fluid into the cylinder 724 to turn the rock shaft 218 in a clockwise direction.

After the rock shaft 218 has turned sufficiently, a switch actuating arm 780 (Fig. 45) secured to the under side of the crank 754 moves upwardly into engagement with a roll 782 on the upper end of a switch arm 784 of a switch 786 (Fig. 44) and moves this arm to close a circuit through this switch. This switch controls the circuit through a solenoid 788 secured to the outside of the leg 12 of the machine frame (Fig. 1). The armature of this solenoid is connected by a link 790 to the upper end of the lever 760 so that the energization of this solenoid returns the lever and the valve member 738 into the positions shown in Fig. 44 whereupon the rock shaft 218 is turned in a counterclockwise direction back to the starting position. Thus, as soon as the crosshead 210 reaches its uppermost position, the valve member 746 is reversed and the crosshead is moved down to carry the upper die downwardly into the position shown in Fig. 24 in which the margin of the work is folded and the fold is pressed.

Provision is made for opening the circuit through the solenoid 768 after the drive shaft has completed its initial turning movement, in the event that the operator should neglect to remove his foot from the toe end of the treadle 640 thus holding it in the position shown in Fig. 49. For this purpose the cam shaft 528 carries a cam 794 which acts on a cam roll 796 (Figs. 48, 50 and 51) carried by an arm 798 of a bell-crank

lever 800 pivoted in a bracket 802 secured to the frame of the machine. The bell-crank lever 800 includes a forwardly extending arm 804, the forward end of which underlies a pin 806 extending laterally from the arm 770. After the cam shaft 528 has rotated somewhat less than 90° from its initial position, shown in Fig. 48, to the position shown in Fig. 50, the bell-crank lever 800 is moved in a clockwise direction and the arm 804 acts on the pin 806 carried by the arm 770 to move this arm upwardly so that the switch arm 776 of the switch 778 is moved by a spring (not shown) in the direction of the arrow (Fig. 50) to open the circuit through the solenoid 768 before the crosshead completes its first upward movement is assured even if the operator neglects to remove his foot from the treadle so that there will be no interference with shifting of the valve member 738 to cause downward movement of the crosshead.

The upper die remains in engagement with the work to press the folded margin, as shown in Fig. 24, for a predetermined length of time, after which the valve member 738 is again shifted to admit pressure fluid into the cylinder 724 to turn the drive shaft 218 in a clockwise direction and raise the upper die to permit removal of the work from the machine. For thus shifting the valve member 738, the mechanism illustrated in Figs. 44 and 52 is provided. Carried by the cam shaft 528 is a cam 810 having a cam groove 812 in a side thereof in which is received a cam roll 814. This cam roll is mounted at the upper end of a lever 816 pivoted on the shaft 762 which carries the lever 760, the lower end of the lever 816 being pivotally connected to a stem 818 of a valve member 820. Before the completion of the downward movement of the upper die the cam 810 causes the lever 816 to move in a counterclockwise direction, thereby moving the valve member 820 to the right.

The valve member 820 is slidable in the valve chamber 734 into which fluid under pressure flows through the passageway 736 and a port 824 (Fig. 53) controlled by an adjustable needle valve 826. Upon movement of the valve member 820 to the right a valve element 828 thereof moves to a position in which it permits the pressure fluid to flow into a passageway 830 leading to a cylinder 832 in which is slidable a piston 834. The piston 834 includes a rod 836 rigid therewith and extending upwardly therefrom. This rod is engageable with the outer end of an arm 838 connected to the lever 760. After the piston has risen sufficiently within the cylinder 832, the lever 760 is moved in a clockwise direction, thereby operating the valve member 738 to admit fluid under pressure into the cylinder 724 so that the rock shaft 218 is moved in a clockwise direction, thus lifting the upper die. The time at which this upper movement of the die takes place is variable, dependent upon the time required to lift the piston 834 sufficiently to operate the lever 760. This time is readily adjusted by the needle valve 826 which regulates the flow of pressure fluid through the small port 824 into the valve chamber 734. Accordingly, the length of time that the upper die remains in pressing engagement with the folded margin of the work is readily adjusted.

The upper die now rises, permitting the operator to remove the work from the machine, and as it reaches the upper limit of its movement the switch arm 784 is again operated by the arm 780 carried by the crank arm 754 to energize the sole-

ranged to support a work piece the margin of which is to be folded, an upper die cooperating with the lower die to turn the margin of the work piece upwardly and fold it back upon the body of the work piece, said lower die having a rubber work-supporting surface arranged to accommodate work pieces of varying thicknesses, and means for moving the upper die.

13. In a form-folding machine, a lower die constituting a work support, an upper die cooperating therewith for folding the margin of a work piece on the lower die, said upper die being arranged to underlie the margin of the work piece prior to the folding operation, and means cooperating with the upper surface of the upper die for pinking the convexly curved marginal portions of the work piece prior to the folding operation.

14. In a form-folding machine, a lower die constituting a work support, an upper die cooperating therewith for folding the margin of a work piece on the lower die, said upper die being arranged to underlie the margin of the work piece prior to the folding operation, a knife cooperating with the upper die for operating upon the margin of the work piece around a curved portion thereof, a spring urging said knife toward the upper die, a latch normally holding said knife in raised position above the upper die, and means operative during the initial upward movement of the upper die in the folding operation for releasing said latch.

15. In a form-folding machine, a lower die constituting a work support, an upper die cooperating therewith for folding the margin of a work piece on the lower die, said upper die being arranged to underlie the margin of the work piece prior to the folding operation, a knife cooperating with the upper die for operating upon the margin of the work piece around a curved portion thereof, a spring urging said knife toward the upper die, a latch normally holding said knife in raised position above the upper die, means operative during the initial upward movement of the upper die in the folding operation for releasing said latch, and means for moving said upper die upwardly a sufficient distance to return said knife to latched position.

16. In a form-folding machine, a lower die constituting a work support, an upper die cooperating therewith for folding the margin of a work piece on the lower die, said upper die being arranged to underlie the margin of the work piece prior to the folding operation, a plurality of knives cooperating with the upper die for slitting and pinking the margin of the work piece along its curved portions, springs urging said knives toward the upper die, spring-pressed latches normally holding said knives in raised positions above the upper die, and means operative during initial upward movement of the upper die in the folding operation for simultaneously moving all said latches to release the knives for downward movement.

17. In a form-folding machine, a lower die constituting a work support, an upper die cooperating therewith for folding the margin of a work piece on the lower die, said upper die being arranged to underlie the margin of the work piece prior to the folding operation, a plurality of knives cooperating with the upper die for slitting and pinking the margin of the work piece along its curved portions, springs urging said knives toward the upper die, spring-pressed

latches normally holding said knives in raised positions above the upper die, means operative during initial upward movement of the upper die in the folding operation for simultaneously moving all said latches to release the knives for downward movement, and means for moving said upper die upwardly a sufficient distance to return said knives to their latched positions.

18. In a form-folding machine, a folding member comprising a plurality of sections mounted for relative adjustment to accommodate work pieces of different sizes, a knife cooperating with one of said sections for operation upon a curved marginal portion of the work piece, and means for adjusting one of said sections and the knife relatively to the other sections.

19. In a form-folding machine, upper and lower folding members, each of said members comprising a plurality of sections mounted for relative adjustment to accommodate work pieces of different sizes, knives associated with the upper folding member to act on curved portions of the work prior to the folding operation, and means for causing simultaneous adjustment of the sections of the upper and lower folding members and of the knives.

20. In a form-folding machine, a lower sectional die forming a work support, means mounting the sections of said die for relative adjustment to accommodate work pieces of different sizes, a sectional upper die arranged to fold the margin of a work piece carried by the lower die, a vertically movable crosshead supporting the upper die, and means carried with the sections of the upper die cooperating with the sections of the lower die to constrain the sections of the upper die for adjustment conjointly with the sections of the lower die.

21. In a form-folding machine, a lower sectional die forming a work support, means mounting the sections of said die for relative adjustment to accommodate work pieces of different sizes, a sectional upper die arranged to fold the margin of a work piece carried by the lower die, a vertically movable crosshead supporting the upper die, means carried with the sections of the upper die cooperating with the sections of the lower die to constrain the sections of the upper die for adjustment conjointly with the sections of the lower die, knives cooperating with the upper die to act on the curved marginal portions of the work piece, means for moving said knives toward the upper die, and means for connecting the knives to the sections of the upper die for adjustment therewith.

22. In a form-folding machine, a lower die arranged to support a work piece the margin of which is to be folded, an upper die movable relatively to the lower die to turn the margin of the work piece upwardly upon movement of the upper die in one direction and to fold the upwardly turned margin and press the fold upon movement of the upper die in the opposite direction, means engageable with the work piece inwardly of the line of fold for holding the work piece on the lower die, and means for moving the holding means into engagement with the work piece and maintaining it there throughout the folding operation.

23. In a form-folding machine, a lower die arranged to support a work piece the margin of which is to be folded, an upper die movable relatively to the lower die to turn the margin of the work piece upwardly upon movement of the upper die in one direction and to fold the upwardly

turned margin and press the fold upon movement of the upper die in the opposite direction, means engageable with the work piece inwardly of the line of fold for holding the work piece on the lower die, means for moving the holding means into engagement with the work piece and maintaining it there throughout the folding operation, means engageable with the convexly curved marginal portions of the work piece for holding them against the adjacent surface of the upper die during its downward movement, and means for retracting said last-named means prior to the completion of movement of the upper die in said opposite direction.

24. In a form-folding machine, upper and lower folding members, each of said members comprising a plurality of sections mounted for relative adjustment to accommodate work pieces of different sizes, means for moving the upper folding member to turn the marginal portion of the work upwardly and then to fold the upwardly turned marginal portion and to press the fold, a plurality of presser feet movable vertically relatively to the lower folding member and engageable with the work along a substantially continuous line inwardly of the edge of the material to be folded, and means for simultaneously adjusting the sections of the upper and lower folding members and the presser feet.

25. In a form-folding machine, a lower die arranged to support a work piece the margin of which is to be folded, an upper die movable relatively to the lower die to turn the margin of the work piece upwardly in response to movement of the upper die in one direction and to fold the upwardly turned margin and press the fold upon movement of the upper die in the opposite direction, a presser foot engageable with the work piece inwardly of the edge of the lower die a sufficient distance so as not to interfere with the folding operation, means for moving and holding the presser foot in engagement with the work piece throughout the folding operation, and means associated with the presser foot for forcing a convexly curved marginal portion of the work piece into engagement with the upper die during its movement to fold the margin of the work piece.

26. In a form-folding machine, a lower die arranged to support a work piece the margin of which is to be folded, an upper die movable relatively to the lower die to turn the margin of the work piece upwardly upon movement of the upper die in one direction and to fold the upwardly turned margin and press the fold upon movement of the upper die in the other direction, a presser foot engageable with the work piece inwardly of the line of fold to hold the work piece in position on the lower die during the folding operation, means for moving and holding the presser foot in engagement with the work piece throughout the folding operation, a corner tool engageable with a convexly curved marginal portion of the work piece and arranged to hold it in engagement with the adjacent surface of the upper die, and means for moving said corner tool into engagement with the work piece prior to movement of the upper die to fold the upwardly turned margin and for retracting said corner tool prior to completion of the movement of the upper die to fold the margin of the work piece.

27. In a form-folding machine, a lower die, an upper die, a presser foot movable into engagement with a work piece on the lower die to clamp the work piece thereon throughout the folding

operation, a corner tool associated with the presser foot to force a convexly curved marginal portion of the work against the upper die during the folding operation, means mounting the corner

5 tool for movement with the presser foot, means normally holding the corner tool in retracted position relatively to the presser foot but permitting its downward movement relatively to the presser foot into operative position, and means 10 for moving the corner tool and presser foot downwardly as a unit to move the presser foot into engagement with the work and for subsequently moving the corner tool into engagement with the work.

15 28. In a form-folding machine, a lower die arranged to support a work piece the margin of which is to be folded, an upper die movable upwardly from a rest position in which it underlies the marginal portion of the work piece to turn 20 up the margin of the work piece, then downwardly to fold the margin and press the fold, then upwardly to permit withdrawal of the work piece, then back to its rest position, and means for automatically moving said upper die through 25 a complete cycle of operations.

29. In a form-folding machine, a lower die arranged to support a work piece the margin of which is to be folded, an upper die movable upwardly from a rest position in which it underlies 30 the marginal portion of the work piece to turn up the margin of the work piece, then downwardly to fold the margin and press the fold, then upwardly to permit withdrawal of the work piece, then back to its rest position, and means 35 for automatically moving said upper die through a complete cycle of operations, said means including means for holding the upper die in pressing engagement with the work for a predetermined period of time.

40 30. In a form-folding machine, a lower die arranged to support a work piece the margin of which is to be folded, an upper die movable upwardly from a rest position in which it underlies the marginal portion of the work piece to turn 45 up the margin of the work piece, then downwardly to fold the margin and press the fold, then upwardly to permit withdrawal of the work piece, then back to its rest position, means for automatically moving said upper die through a complete cycle of operations, said means including means for holding the upper die in pressing engagement with the work for a predetermined period of time, and means for adjusting said last-named means to vary said period of time.

55 31. In a form-folding machine, a lower die arranged to support a work piece the margin of which is to be folded, an upper die movable upwardly from a rest position in which it underlies the marginal portion of the work piece to turn 60 up the margin of the work piece, then downwardly to fold the margin and press the fold, then upwardly to permit withdrawal of the work piece, then back to its rest position, and fluid-pressure-operated means for moving said upper die through a complete cycle of operations.

65 32. In a form-folding machine, a lower die arranged to support a work piece the margin of which is to be folded, an upper die movable upwardly from a rest position in which it underlies the marginal portion of the work piece to turn up the margin of the work piece, then downwardly to fold the margin and press the fold, then upwardly to permit withdrawal of the work piece, then back to its rest position, and fluid-

pressure-operated means for moving said upper die through a complete cycle of operations, said fluid-pressure-operated means including means for holding the upper die in pressing engagement with the work for a predetermined period of time.

33. In a form-folding machine, a lower die arranged to support a work piece the margin of which is to be folded, an upper die movable upwardly from a rest position in which it underlies the marginal portion of the work piece to turn up the margin of the work piece, then downwardly to fold the margin and press the fold, then upwardly to permit withdrawal of the work piece, then back to its rest position, and fluid-pressure-operated means for moving said upper die through a complete cycle of operations, said fluid-pressure-operated means including an adjustable timing-valve mechanism arranged to hold the upper die in pressing engagement with the work for a predetermined period of time.

34. In a form-folding machine, means for supporting a work piece the margin of which is to be folded, a knife arranged to act on a curved marginal portion of the work piece, a spring for moving said knife into engagement with the work, a latch for holding said knife elevated against the force of said spring, means for releasing said latch, and fluid-pressure-operated means for moving said knife against the force of said spring into latching position.

35. In a form-folding machine, a lower die comprising a work support, an upper die for folding the margin of a work piece on the lower die, means for holding a work piece on the lower die, power-operated means for moving said holding means into operative position, power-operated means for moving the upper die to fold the margin of the work and to press the folded margin, a treadle, means controlled by the treadle upon depression of one end thereof for placing said first power-operated means in operation, and means controlled by the treadle upon depression of the other end thereof for placing said second power-operated means in operation.

36. In a form-folding machine, a lower die arranged to support a work piece, an upper die movable vertically relatively to the lower die to fold the margin of the work piece, a rock shaft, means connecting the rock shaft to the upper die, and fluid-pressure-operated means for oscillating said rock shaft.

37. In a form-folding machine, a lower die arranged to support a work piece the margin of which is to be folded, an upper die movable upwardly from a rest position in which it underlies the edge of the work piece to turn up the margin of the work piece, then downwardly to fold the margin and press the fold, then upwardly to permit withdrawal of the work piece, then back to its rest position, a rock shaft, means connecting said rock shaft to the upper die, and fluid-pressure-operated means for imparting two oscillations to said rock shaft to move the upper die through a complete cycle.

38. In a form-folding machine, a lower die arranged to support a work piece the margin of which is to be folded, an upper die movable upwardly from a rest position in which it underlies the edge of the work piece to turn up the margin of the work piece, then downwardly to fold the margin and press the fold, then upwardly to permit withdrawal of the work piece, then back to its rest position, a rock shaft, means

connecting said rock shaft to the upper die, fluid-pressure-operated means for imparting two oscillations to said rock shaft to move the upper die through a complete cycle, and means controlling said fluid-pressure-operated means to delay operation of the rock shaft for a predetermined period of time while the upper die is in pressing engagement with the folded portion of the work.

39. In a form-folding machine, a lower die arranged to support a work piece, an upper die movable vertically relatively to the lower die to fold the margin of the work piece, a rock shaft, means connecting said rock shaft to the upper die, fluid-pressure-operated mechanism for oscillating said rock shaft, said fluid-pressure-operated mechanism including a pair of fluid-pressure-operated members, and means for alternately admitting fluid pressure to said members.

40. In a form-folding machine, a lower die arranged to support a work piece, an upper die movable vertically relatively to the lower die to fold the margin of the work piece, a rock shaft, means connecting said rock shaft to the upper die, a pair of fluid-pressure-operated members, means connecting said members to said rock shaft to oscillate the shaft, and means for alternately admitting pressure fluid to said fluid-pressure-operated members, said means including a timing mechanism arranged to cause the upper die to remain in contact with the work for a predetermined period of time.

41. In a form-folding machine, a folding member comprising a pair of sections adjustable relatively to each other to accommodate work pieces of different sizes, and means associated with said sections movable into the space between the sections upon their separation, thereby to provide a substantially continuous edge along the folding member.

42. In a form-folding machine, a folding member comprising a pair of sections adjustable relatively to each other to accommodate work pieces of different sizes, said sections being separated at substantially straight line portions, and filler pieces substantially rectangular in cross section associated with said sections and movable into the space between the sections upon their separation, thereby to provide a substantially continuous edge along the folding member.

43. In a form-folding machine, a folding member comprising a pair of sections adjustable relatively to each other to accommodate work pieces of different sizes, a plurality of filler pieces associated with said sections and movable into the space between the sections upon their separation, and means for moving the filler pieces into position between the sections in a sufficient number substantially to fill the space.

44. In a form-folding machine, a folding member comprising a pair of sections adjustable relatively to each other to accommodate work pieces of different sizes, a plurality of filler pieces associated with said sections and movable into the space between the sections upon their separation, and springs acting on said filler pieces for moving them into position between the sections in a sufficient number substantially to fill the space.

45. In a form-folding machine, a folding member comprising a pair of sections adjustable relatively to each other to accommodate work pieces of different sizes, a plurality of filler pieces associated with said sections and movable into the space between the sections upon their separation, and means for moving the filler pieces into position

between the sections in a sufficient number substantially to fill the space, and means for locking said filler pieces in said positions.

46. In a form-folding machine, a folding member comprising a pair of sections adjustable relatively to each other to accommodate work pieces of different sizes, a plurality of filler pieces associated with said sections and movable into the space between the sections upon their separation, means for moving the filler pieces into position between the sections in a sufficient number substantially to fill the space, and a locking member common to all said filler pieces for locking them in said positions.

47. In a form-folding machine, a folding member comprising a pair of sections adjustable relatively to each other to accommodate work pieces of different sizes, a plurality of filler pieces associated with said sections and movable into the space between the sections upon their separation, means for moving the filler pieces into position between the sections in a sufficient number substantially to fill the space, and means for retracting said filler pieces to permit movement of said sections toward each other.

48. In a form-folding machine, a folding member comprising a pair of relatively adjustable sections, a set of filler pieces movable from retracted positions to operative positions between the sections upon their separation to maintain the continuity of the sections, means including a latch engageable with the filler pieces to maintain them in operative positions, and an arm engageable with said filler pieces for retracting the filler pieces to permit relative movement of the sections toward each other, said arm including means for releasing the latches to permit retraction of the filler pieces.

49. In a form-folding machine, a sectional die providing an edge defining the line of fold of a work piece, supporting members for the sections of said die, means for adjusting the relative positions of the supporting members to accommodate work pieces of different sizes, and means carried by one of the supporting members movable into the position between the sections of the die upon their separation to maintain the continuity of the edge.

50. In a form-folding machine, a sectional die providing an edge defining the line of fold of a work piece, supporting members for the sections of said die, means for adjusting the relative positions of the supporting members to accommodate work pieces of different sizes, a plurality of filler pieces carried by one of the supporting members, said filler pieces being movable into positions between the dies upon their separation to provide a substantially continuous edge along the folding member.

51. In a form-folding machine, a sectional die providing an edge defining the line of fold of a work piece, supporting members for the sections of said die, means for adjusting the relative positions of the supporting members to accommodate work pieces of different sizes, a plurality of filler pieces carried by one of the supporting members, said filler pieces being movable into positions between the dies upon their separation to provide a substantially continuous edge along the folding member, and means for locking the filler pieces in operative positions.

52. In a form-folding machine, a sectional die providing an edge defining the line of fold of a work piece, supporting members for the sections of said die, means for adjusting the relative positions of the supporting members to accommodate

work pieces of different sizes, a plurality of filler pieces carried by one of the supporting members, said filler pieces being movable into positions between the dies upon their separation to provide a substantially continuous edge along the folding member, means for locking said filler pieces in operative positions between the sections of the die, and means for retracting the filler pieces to permit relative movement of the sections of the die toward each other, said retracting means including means for releasing the locking means.

53. In a form-folding machine, a work support comprising a plurality of supporting blocks, each of said blocks being provided with a yielding work supporting surface providing an edge defining the line of fold of a work piece supported thereon, means for adjusting the positions of the supporting blocks relatively to each other to accommodate work pieces of different sizes, means associated with said supporting blocks movable into the spaces formed between the blocks to provide a substantially continuous edge along the work support, and means mounting said last-named means for yielding movement with the yielding surfaces of the blocks.

54. In a form-folding machine, a work support comprising a plurality of supporting blocks, each of said blocks being provided with a yielding work-supporting surface providing an edge defining the line of fold of a work piece supported thereon, means for adjusting the positions of the supporting blocks relatively to each other to accommodate work pieces of different sizes, a plurality of filler pieces associated with said supporting blocks movable into the spaces formed between the blocks to provide a substantially continuous edge along the work support, and means mounting said filler pieces for yielding movement with the yielding surfaces of the blocks.

55. In a form-folding machine, a folding member comprising a pair of sections adjustable relatively to each other to accommodate work pieces of different sizes, each of said sections being provided with a yielding work-supporting surface providing an edge defining the line of fold of a work piece supported thereon, a plurality of filler pieces carried by one of said sections for limited vertical movements and for movement into the space between the sections to maintain the continuity of the edge, and means acting on said filler pieces to maintain the top surface flush with the work-supporting member.

56. In a form-folding machine, a folding member comprising a pair of sections adjustable relatively to each other to accommodate work pieces of different sizes, each of said folding sections being provided with a yielding work-supporting surface providing an edge defining the line of fold of a work piece supported thereon, a plurality of filler pieces carried by one of said sections for limited vertical movements and for movement into the space between the sections to maintain the continuity of the edge, means acting on said filler pieces to maintain the top surface flush with the work-supporting member, latches for locking said filler pieces in operative positions between the sections of the folding member, and means for releasing said latches and for retracting the filler pieces to permit movement of said sections toward each other.

57. In a form-folding machine, upper and lower folding members, each of said members comprising a plurality of sections mounted for relative adjustment to accommodate work pieces of different sizes, and means associated with each

of said sections and arranged for movement upon separation of said sections into the spaces between the sections of each member to provide a substantially continuous edge along said folding members.

58. In a form-folding machine, upper and lower folding members, each of said members comprising a plurality of sections mounted for relative adjustment to accommodate work pieces of different sizes, and means associated with each of said sections and arranged for movement into the spaces between the sections of each member automatically in response to separation of said sections thereby to provide a substantially continuous edge along said folding members.

59. In a form-folding machine, upper and lower folding members, each of said members comprising a plurality of sections mounted for relative adjustment to accommodate work pieces of different sizes, means for simultaneously adjusting the sections of the upper and lower folding members, and means operative in response to separation of the sections for filling the spaces between the sections to provide substantially continuous edges along said folding members.

60. In a form-folding machine, upper and lower folding members, each of said members comprising a plurality of sections mounted for relative adjustment to accommodate work pieces of different sizes, and a set of filler pieces associated with the sections of the folding members and movable from retracted positions into positions between the sections during separation thereof to maintain the continuity of the edges of the folding members.

61. In a form-folding machine, upper and lower folding members, each of said members comprising a plurality of sections mounted for relative adjustment to accommodate work pieces

of different sizes, a set of filler pieces associated with the sections of the folding members and movable from retracted positions into positions between the sections during separation thereof to maintain the continuity of the edges of the folding members, and means for retracting the filler pieces to permit movement of the sections toward each other.

5 62. In a form-folding machine, upper and lower folding members, each of said members comprising a plurality of sections mounted for relative adjustment to accommodate work pieces of different sizes, a set of filler pieces associated with the sections of the folding members and movable from retracted positions into positions between the sections during separation thereof to maintain the continuity of the edges of the folding members, means for locking the filler pieces in operative positions, and means for releasing said locking means and for retracting the filler pieces to permit movement of the sections toward each other.

10 63. In a form-folding machine, upper and lower folding members, each of said members comprising a plurality of sections mounted for relative adjustment to accommodate work pieces of different sizes, a set of filler pieces associated with the sections of the folding members and movable from retracted positions into positions between the sections during separation thereof to maintain the continuity of the edges of the folding members, means for locking the filler pieces in operative positions, means for releasing said locking means and for retracting the filler pieces to permit movement of the sections toward each other, and single means for operating said last-named means.

JOSEPH FOSSA.

CERTIFICATE OF CORRECTION.

Patent No. 2,379,074.

June 26, 1945.

JOSEPH FOSSA.

It is hereby certified that error appears in the printed specification of the above numbered patent requiring correction as follows: Page 11, first column, line 58, strike out the words "as the die reaches its uppermost position the" and insert instead --ing shifted to the right and the presser feet in--; and second column, line 31, for "came" read --cam--; line 38, for "disc" read --die--; and that the said Letters Patent should be read with this correction therein that the same may conform to the record of the case in the Patent Office.

Signed and sealed this 16th day of October, A. D. 1945.

Leslie Frazer

(Seal)

First Assistant Commissioner of Patents.
